(57) **CLAIM**

We claim the ornamental design for a specimen analyzer, as shown and described.

DESCRIPTION

FIG. 1 is a front view of a specimen analyzer of the present invention;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a top and front perspective view thereof; and,

FIG. 8 is a top and front perspective view thereof shown in an environmental use.

The broken lines in FIG. 8 represent the environmental subject matter, and the broken lines in FIGS. 2 and 4 are included for the purpose of illustrating portions of the specimen analyzer that form no part of the claimed design. None of the broken lines form a part of the claimed design.
